UNITED STATES PATENT OFFICE.

JOHN E. AHLVIN, OF JOLIET, ILLINOIS.

EDGE PLANER.

Application filed July 24, 1926. Serial No. 124,654.

This invention relates particularly to an edge-planer adapted to the purpose of planing the edges of doors, windows, etc.

As is well known, doors and windows, or frames thereof, ordinarily are made in sash and door factories. Usually, they are made somewhat oversize and require to be fitted to the frames of the openings which are to receive them at the building which is being erected.

Prior to the present invention, it has been customary for workmen to trim the edges of the door frames, or window frames, as the case may be, by means of hand planers. Such work is extremely laborious, difficult to perform with the desired degree of accuracy and requires the expenditure of an excessive amount of time. The work of trimming heavy doors, in particular, has hitherto been exceedingly laborious and unnecessarily expensive.

The primary object of the present invention is to provide an edge-planing device by means of which an operator can trim the edges of heavy doors, for example, with great facility and with thorough accuracy.

The improved edge-planer, moreover, is adapted to produce either a square edge or a slightly undercut edge, as may be desired.

The invention is illustrated in its preferred embodiment in the accompanying drawings, in which—

Fig. 1, is a broken plan view of a door having a template (shown brokenly) mounted thereon, the view showing also the improved edge-planer mounted on the template; Fig. 2, a broken sectional view illustrating adjustable means with which the edge-planer is equipped for gaging the depth of cut; Fig. 3, a broken vertical sectional view taken as indicated at line 3 of Fig. 5; Fig. 4, a vertical sectional view taken as indicated at line 4 of Fig. 1; Fig. 5, a broken edge view of the door and template, showing the planer in position; and Fig. 6, a broken horizontal sectional view taken as indicated at line 6—6 of Fig. 4.

In the illustration given, A designates a door; A', a template placed upon the door and suitably secured thereto, as by clamping means (not shown); and B the improved edge-planer, or edge-trimming device.

In the illustration given, the template A' is of rectangular form and of approximately

the dimensions of the door. It is shown as comprising steel strips 1 which are suitably joined by means not shown to form a rectangle. Preferably, each of the strips 1 is equipped with narrow wooden strips 1^a upon which the planer can slide.

The edge-planer B, in the illustration given, comprises a base-plate B' having a flat, smooth, lower surface and equipped at one lateral edge with a depending guide-flange 2; an electric motor B² mounted on the plate B'; and a cutter-housing B³ carried by and depending from the flange 2, and having journalled therein a vertically disposed revolving cutter B⁴.

The base-plate B' is adapted to rest in horizontal position upon the template A', which, in turn, surmounts the work, which may consist of a door frame, window frame, or the like. The plate B' preferably is about eighteen inches in length, and is equipped with handles 3 and 4 by means of which the planer may be manipulated by the workman. The plate is further equipped with a standard, or standards, 5, formed integrally with the plate and rising therefrom. The frame of the motor B² is equipped with lugs 6 which are secured to the members 5, and with lugs 7 which are secured to the base-plate B', as by means of cap screws 8. The

guide-flange 2 is provided at its inner surface with a longitudinal groove 9 (Figs. 2 and 4), in which is located a guide-bar 10. This guide-bar is equipped at its end portions with headed studs 11 which work through perforations with which the flange 2 is provided. Springs 12 are interposed between the heads of said studs and the bottoms of the counter-sinks in which the heads of the studs work. The guide-flange 2 is equipped with lugs 13 equipped with pivots 14 upon which are mounted adjusting levers 15 provided with cam-heads 15^a, which are so formed that the guide-bar 10 can be adjusted in either of three positions, viz, in a completely sheathed position, in an intermediate position, or in a completely projected position. The cams are provided with flattened surfaces so that the levers will be locked in any adjusted position. It will be understood that by means described, the guide-bar 10 may be adjusted to gage the depth of cut.

The cutter housing B³ preferably is

equipped with a cutter 16 which is secured to the housing by means of a set-screw 17. The cutter 16 is provided with a cutting edge 18 which is

adjustable in height by means of a lever 19 which is secured to the cutter housing B³ by means of a set-screw 20. The lever 19 is provided with a cam 21 which is

adjustable in height by means of a lever 22 which is secured to the cutter housing B³ by means of a set-screw 23. The lever 22 is provided with a cam 24 which is

adjustable in height by means of a lever 25 which is secured to the cutter housing B³ by means of a set-screw 26. The lever 25 is provided with a cam 27 which is

adjustable in height by means of a lever 28 which is secured to the cutter housing B³ by means of a set-screw 29. The lever 28 is provided with a cam 30 which is

formed integrally with the base-plate B' and its guide-flange 2. The housing projects a sufficient distance below the plane of the base-plate to enable the knives of the cutter to properly engage the edge of the "work" being trimmed. The housing is shown as comprising a cylindrical member having its inner half, or somewhat more than its inner half, cut away to enable the cutter to engage the edge of the door.

The cutter B⁴ comprises a shaft 16, a body portion 16^a, and adjustable blades 16^b. The shaft 16 is journaled in anti-friction bearings 17 with which the housing is equipped. These bearings are shown diagrammatically. In practice, they will be of such character as to afford a thrust bearing for the cutter. The upper end of the shaft 16 is connected by a suitable connection 18 with the lower end of the shaft 19 of the superposed motor B.

Preferably, the axis of the cutter is vertical, and the edges of the blades 16^b incline somewhat, as indicated at 16^c in Fig. 3, so as to produce a desired amount of under cut on the edge of the door. If it be desired to take a right-angle cut, this may be accomplished by placing a shim-strip over the outer strip 1^a of the template, thus elevating the outer edge of the base-plate B' slightly.

The blades 16^b are adjustably secured to the body portion 16^a of the cutter by means of cap-screws and slots, as indicated at 20.

As shown in Fig. 3, the upper end of the shaft 16 is provided with a flange which forms a part of the connection 18. Therefore, the shaft must, in this construction, be inserted into the bearing from above. The bearing at the lower end of the housing B³ has a removable section 21, this section being secured to lugs 22 by means of cap-screws 21^a.

The method of using the edge-planer may be described briefly: The work, such as a door or sash, may be supported on a bench C. The template A' is placed upon the door and clamped thereto by suitable means (not shown). The template thus serves as a straight edge against which the guide flange 2 of the base-plate B' of the implement may bear. The workman shoves the plane along the template while the cutter operates to trim the edge of the door. The depth of the cut may be regulated by adjusting the guide-bar 10 carried by the guide-flange 2, this adjustment being accomplished by means of the cam-levers 15. The finishing cut may be a light one. In the planing operation, the base-plate B' rides on the strips 1^a of the template. The blades of the cutter are so formed as to produce a slight undercut on the edge of the door, as will be understood from Fig. 3. If desired, however, a shim-strip (not shown) may be placed on the strip 1^a which is at the edge of the door and

thus bring the cutting edge to a perpendicular position, so as to produce a right angle edge.

By means of the improved implement, it is possible for a workman to trim, or plane, the edges of a large number of heavy doors in a day, and the work can be done with great facility and accuracy. The output per workman may be increased several fold by employing the improved implement. This is a matter of very great importance in fitting the doors of buildings which are provided, in some instances, with hundreds of doors.

The foregoing detailed description has been given for clearness of understanding only and no unnecessary limitations should be understood therefrom, but the appended claims should be construed as broadly as permissible in view of the prior art.

What I regard as new, and desire to secure by Letters Patent, is:

1. An edge-planer comprising a base-plate equipped at its upper side with handles and at one lateral edge with a depending guide-flange and depending cutter-housing; a motor mounted on said plate; and a revolving cutter journaled in said housing and actuated by said motor.

2. An edge-planer comprising a base-plate equipped at its upper side with handles and at one lateral edge with a guide-flange; a vertical revolving cutter journaled at one lateral edge of said plate and depending below said guide-flange; and a vertical motor mounted on said guide-plate and having its armature shaft connected directly with the shaft of said cutter.

3. An edge-planer comprising a base-plate equipped at one lateral edge with a depending guide-flange which is provided with a longitudinal groove, a guide-bar mounted in said groove, means for adjusting said guide-bar to gage the depth of cut, a motor mounted on said base-plate, a cutter housing depending from said base-plate, and a vertical rotary cutter journaled in said housing below the plane of said guide-flange and actuated by said motor.

4. In combination: a rectangular template; a base-plate adapted to slide on said template and equipped at one lateral edge with a guide-flange adapted to engage an edge of the template; handles on said base-plate, a motor mounted on said base-plate, and a vertical rotary cutter journaled at one edge of said base-plate and disposed below the plane of the base-plate, said cutter being actuated by said motor.

5. An edge-planer comprising a base-plate equipped with handles and with a depending guide-flange; an adjustable guide-bar connected to said guide-flange and substantially co-extensive in length therewith; a motor mounted on said base-plate; and a re-

volving vertical cutter depending below the plane of said guide-flange and actuated by said motor.

6. An edge-planer comprising a base-plate equipped at its upper side with handles and a standard and equipped at one lateral edge with a depending guide-flange; a vertical motor having a frame secured to said base-

plate and to said standard; a vertical housing formed integrally with said base-plate ¹⁰ and depending therefrom; and a revolving cutter mounted in said housing and having a shaft connected directly with the armature shaft of said motor.

JOHN E. AHLVIN.
